UNITED STATES PATENT OFFICE.

JOSEPH ADDISON SANDFORD, JR., OF EAST LIVERPOOL, OHIO, ASSIGNOR TO THE R. THOMAS AND SONS COMPANY, OF EAST LIVERPOOL, OHIO, A CORPORATION OF OHIO.

INSULATOR.

1,093,479.

Specification of Letters Patent. Patented Apr. 14, 1914.

Application filed December 16, 1911. Serial No. 866,273.

To all whom it may concern:

Be it known that I, JOSEPH ADDISON SANDFORD, Jr., a citizen of the United States of America, and residing at East Liverpool, in the county of Columbiana and State of Ohio, have invented a certain new and useful Improvement in Insulators, of which the following is a specification.

My present invention relates to insulators and particularly to an insulator of the pin type, the object of my invention being to provide an insulator of this type adapted to carry electric power cables of very high voltage.

15 In the accompanying drawing, an exemplary embodiment of my invention is illustrated, half in side elevation and half in vertical section.

The present practice in the stringing of power cables of high voltage is to hang the same from insulators of the suspension type. Insulators of the latter type consist of several porcelain disks suspended one under the other by means of metal units, comprising 20 hooks and caps carried respectively by the upper and lower insulators. The presence of the considerable amount of metal which is thus necessary at the joint between the insulator units is detrimental to the efficiency of 25 the insulator as a whole, since the metal forms a condenser, the effect of which is to increase the current leakage and the danger of arcing. By reason of this inherent deficiency, it has been found impossible to 30 safely carry very high power cables without increasing the number of units in each suspension insulator to such an extent as to make the expense incident to such an installation very great.

35 The present insulator is of the pin type and comprises a cap unit A, the top of which is specially shaped to afford a diametral cable groove *a* and a circumferential securing wire groove *b*, by which the cable may be 40 tied in position in the groove *a*. Beneath the cap insulator A, I provide a series of interchangeable bell insulator units B, the number of which may be multiplied to the extent necessary to secure the desired protective insulation space between the cable and

45 pin. The units B are of any desired size and thickness, but are designed so that the upper portion of each shall fit well up within the lower portion of the unit above the 50 same, the juxtaposed or meeting faces of the

units B being provided with recesses or ribs *c* or *d* to insure a mechanical jointure with the cement C interposed between the meeting faces. It will be noted that the top of one bell B extends up within the superposed bell B to a point a little above the lower edge of the cementing space between the latter and its superposed bell, so that at this point there is a thickness of the walls of three bells and two layers of interposed cement, while at no point in the composite insulator structure is there a thickness of less than the walls of two units. At the same time it will be noted that the diaphragm D at the upper end of the bell forms 60 a strut extending between the opposite sides of one unit at its joint with its superposed unit. It is thus obvious that each of the joints between the various B units of the insulator is one of great mechanical strength. 65

The pin P on which the insulator is mounted, extends only into the bottom unit B, and is therefore very far removed from the transmission cable, and due to this fact the tendency of the insulator to puncture 70 is greatly reduced. In fact the construction is such that care has only to be taken that a sufficient distance is obtained by the use of a suitable number of the B units to minimize 75 leakage from the cable to the pin under dry conditions, and arcing from the cable to the pin under rain or storm conditions.

The absence of any metallic elements and the consequent absence of the condenser effect, present in insulators of the suspension type, greatly increases the electrostatic capacity of the present insulator and it is possible to build up an insulator of this type to carry a cable charged under a working pressure of 120,000 volts. 80

85 From a manufacturer's standpoint the value of the present insulator is readily seen, since the cap unit A may be used with as many or as few B units as the line voltage may require. In view of the fact that the B units are identical in form, they may be manufactured in large quantities and used for building up insulators of only the particular capacity which may be required. 90

95 I claim as my invention:—

1. A built-up insulator comprising interchangeable, nested units, top-closure diaphragms for each of said units, said diaphragms being spaced apart and serving to form inclosed air chambers, cementitious 100

110

material uniting the units, the joint between one unit and its superposed unit overlapping the joint between the latter and the unit next above, for the purpose described.

2. A built-up insulator comprising a cap-unit shaped to receive an electric cable, a series of interchangeable nested insulator units beneath the same, top-closure diaphragms for said units, said diaphragms being spaced apart to form inclosed air chambers, cementitious material uniting the units, the joint between one unit and its super-

posed unit overlapping the joint between the latter and the unit next above, the bottom unit of the series receiving the supporting pin, substantially as described. 15

In testimony whereof I have signed my name to this specification, in the presence of two subscribing witnesses.

JOSEPH ADDISON SANDFORD, JR.
